UNITED STATES PATENT OFFICE.

HENRY AYLMER, OF SHERBROOKE, CANADA, ASSIGNOR TO AYLMER DRILL MANUFACTURING COMPANY, OF MONTREAL, CANADA.

DESIGN FOR A ROCK-DRILL STOCK.

SPECIFICATION forming part of Design No. 34,835, dated July 23, 1901.

Application filed February 16, 1901. Serial No. 47,704. Term of patent 14 years.

To all whom it may concern:

Be it known that I, HENRY AYLMER, a subject of His Majesty the King of Great Britain, residing at Sherbrooke, in the county of Sherbrooke, in the Province of Quebec, Canada, have invented and produced a new and original Design for Rock-Drill Stocks, of which the following is a specification, reference being had to the accompanying drawings, forming part thereof.

Figure 1 is a perspective view of a drill-stock, showing my design. Fig. 2 is a sectional view of the same.

The leading feature of my design consists of an elongated body having a central polygonal body and rounded ends with notches in

the edge of the lower end, said lower end having an axial opening and a pin passing through and slightly entering the opening.

The polygonal body is shown at A, the upper round portion at A', the lower round portion at a², the notches at B, the axial opening at D, and the pin at C.

I claim—

The design for a rock-drill stock substantially as shown and described.

Signed at Sherbrooke this 19th day of November, 1900.

HENRY AYLMER.
